UNITED STATES PATENT OFFICE.

WILLIAM EDWARD MURRAY, OF LOS ANGELES, CALIFORNIA.

STEADY FOUNDATION FOR FLOATING STRUCTURES.

No. 825,149.

Specification of Letters Patent.

Patented July 3, 1906.

Application filed April 15, 1905. Serial No. 256,773.

To all whom it may concern:

Be it known that I, WILLIAM EDWARD MURRAY, a subject of the King of Great Britain and Ireland and Emperor of India, of 5 Edinburgh, North Britain, commonly called Scotland, at present residing in the city of Los Angeles, in the county of Los Angeles, in the State of California, have invented Steady Foundations for Floating Structures.

10 My improved foundations are adapted for carrying the above-water parts of floating breakwaters, floating fortresses, floating wharves, floating light houses, and analogous structures, such as harbors, moles, jetties, or piers, floating coaling-stations, and floating docks or docky ards in mid-ocean, steadiness of all of which structures while floating is by my new or improved foundations maintained.

15 The following is a full, clear, and exact description or specification, reference being had to the annexed drawings and to the letters marked thereon.

20 My said invention has for its object to provide a steady floating foundation having displacement capability greater than that due to the weight of the structure itself. This object is brought about by the structure having volume of immersion not only considerably greater than the volume of its immersed portion, but also by loading or weighting part of the volume of immersion, so that the load or weight carried while being always equilibrated—that is to say, balanced—is so disposed around the axes of and at the bottom of the structure, also at such sufficient distance laterally or horizontally on both sides of the horizontal axis, and, when the foundation is circular, at all points equidistantly 35 from the center of the floating foundation, that the structure when immersed to the required depth below the surface is practically incapable of disturbance or of being rocked in or by the waves of the ocean or other body 40 of water in which it is floated. This increased steadiness of flotation is brought about by loading the foundation, in part at least and in some cases to a considerable extent, with a substance having a density 45 greater than the density of water. Such heavier substance I find ready for use as a natural product, and without requiring manufacturing, in the gravels which are always present on shores subject to tidal and wave 50 action. With such gravel, which is considerably greater in density than water, some-

times nearly of twice the density, I load several of the receptacles which are provided in the lower part of the structure and arranged at sufficient distance on either side from the 60 central horizontal axis of the foundation when elongated in form, and arranged in a circle around the vertical axis when the foundation is circular in form, to insure this load of gravel, by reason of its superior density 65 above that of water and being arranged at considerable distance from the axes referred to, producing a maximum steady effect.

In what I have thus far set forth I have stated several of the applications of my invention and the fundamental principles upon which my invention is based, and I furthermore state that while form or shape of my steady floating foundation does not constitute any essential feature of my invention, 75 yet there are some forms or shapes thereof better adapted for some uses or applications thereof than are other forms. For example, a longitudinal rectangular form of foundation is best adapted for carrying the 80 above-water parts of floating breakwaters, floating wharves, floating moles, or jetties, while a circular form of foundation is best adapted for carrying a stationary or revolving fortress or a lighthouse.

I now proceed to illustrate by describing the annexed drawings some of the forms of the steady floating foundations which are best adapted to carry out the main objects of my invention.

Upon the drawings, Figure 1 is a front elevation of a single length or section of my steady floating foundation when used for carrying the upper part of a floating breakwater. Its foundation consists of a heavy 95 floating body constructed and loaded with weight, as herein described. The breakwater part carried upon my steady floating foundation rises, as is usual with all breakwaters, to a sufficient height above the waves 100 for the waves to strike against and be broken up on the starboard side by impact therewith as the waves roll and strike against the starboard side of the above-water part of a breakwater in the well-known manner either 105 in the ocean or other body of water. The upper breakwater portion carried upon my new or improved steady floating foundation does not constitute any part of my present invention. Fig. 2 is a plan corresponding to 110 Fig. 1. Fig. 3 is a transverse section of the same on the line *a a*, Figs. 1 and 2. Fig. 4 is

a front elevation; Fig. 5, a part plan; Fig. 6, a transverse section on the line *b b*. Figs. 5 and 6 of the foundation are identical with that shown at Figs. 1, 2, and 3, but shown as carrying a superstructure of somewhat 5 slightly different construction to that shown at Figs. 1, 2, and 3. Fig. 7 is another front elevation of the same submerged foundation as that shown in the preceding Figs. 1 to 6. 10 Fig. 8 is a part plan; and Fig. 9, a transverse section on the line *c c*, Figs. 7 and 8. Fig. 10 is an enlarged transverse section corresponding to Fig. 9 and showing more of the details of construction. Fig. 11 is a side elevation, 15 with certain parts in section, of the same or identical structure in respect of the steady floating foundations and the above-water parts of a breakwater as is that shown at Figs. 1 to 10, but in which an additional feature, not, however, as part of this invention, 20 is shown, which is capable of being used when a breakwater or analogous structure is to be placed in deeper water—that is, farther from a shore—than is contemplated by or in 25 accordance with the drawings Figs. 1 to 10. Fig. 12 is an elevation, and Fig. 13 a plan, of my steady floating foundation formed circular for carrying a circular floating fortress.

In a former application for Letters Patent, 30 filed on the 2d day of August, 1904, Serial No. 219,246, the steadiness of the floating structures therein shown and described is in part brought about by heavy movable weights suspended over sheaves by chains 35 whose outer ends are fastened by anchors to the bed of the ocean, while the weights, as well as the structures, both rise and fall with the tide by reason of the freedom to so move being rendered practicable because of the 40 suspension of the weights by suspension-chains carried over the sheaves.

Under my present invention I dispense with this arrangement of weights suspended from chains and passed over sheaves to anchors and dispose all the weight which produces 45 steadiness of flotation by filling or in part filling the compartments in the steady floating foundations with material preferably of heavier relative density than water.

In the drawings, Figs. 1 to 3, inclusive, the foundation of the hollow rectangular projecting flanged bottom *A*, which is continuous through the length of each section or division of a floating breakwater's length, or if the 55 floating breakwater is in one length then the bottom *A* is continuous—that is to say, in one part—throughout the entire length thereof. This steady floating foundation, rectangular in vertical, transverse, and horizontal 60 section, as shown by the drawings, is stayed and braced and stiffened internally by girders, tension-rods, angle and **T** or channel irons and gussets, such as are commonly used for bracing and stiffening other large structures of iron and steel, the whole of which

parts are riveted and bolted and tied together, according to the general practice of engineers and naval architects, to produce the stiffest structures with a sufficient factor of safety consistent with the stresses which such structures have to withstand, according to their various purposes of utility. Such stiffening or bracing cannot be completely shown in drawings restricted to the dimensions of sheet allowed under the Rules of Practice of the Patent Office; but such stiffening or bracing is shown to some extent in the drawings to indicate its nature sufficiently to guide and instruct persons skilled in the art of construction in iron and steel. The stiffening or bracing of the foundations constitutes no part of my invention, which is capable of being carried out with the many methods of stiffening and bracing so well known to and commonly practiced by 85 engineers and naval architects and generally in use that it need not be herein further referred to.

Upon the aforesaid foundation *A* there is carried the breakwater, consisting of a series 90 of cylinders *B B B B* &c., connected with the foundation *A* so as to be securely fastened thereto and situated vertically thereon. These cylinders are united by stiff rectangular divisions *C* of steel plates filling the space 95 between each pair of cylinders *B B B B*, &c., being securely riveted to the top plates of the foundation *A* and to the exteriors of the cylinders *B B B*, &c., and interiorly stayed by **T**-iron rings *D*, as shown in section at Fig. 3, 100 and by such other bracing as may be placed throughout the cylinders *B* and the rectangular divisions *C*, the whole of which are riveted together and to the bracing.

The breakwater or its analogue is moored 105 to the floor or bottom *D'* of the ocean or other body of water by anchors *E*, which are connected by protected steel-wire hawsers *F* to the winches, one of which is indicated at the part in section in Figs. 1 and 2, (marked *G*.) 110 The winding-barrels *G* of the winches are operated to at all times permit the hawsers *F* being loosely suspended in the manner shown at Fig. 1, and it is explained that the anchors *E* are not for the purpose of holding 115 the breakwater or its steady floating foundation taut or in a definitely-fixed situation, but are for the purpose of sufficiently controlling any range of motion horizontally 120 which the foundation may be subject to the influence of, such as undercurrents or undertow in any direction, while there is sufficient slack in the hawsers *F* to admit of the foundation and any structure erected thereon rising and falling with the rise and fall of the tide. In cases where there is excessive undertow, currents, tidal or wave disturbance 125 the ends of the foundations may be still further stayed by a group of hawsers *H H H* *H* with corresponding anchors, being let fall 130

over the ends of the foundation, as shown at Figs. 1 and 2.

To stiffen the structure transversely, the triangular stiffening-braces II, Figs. 1, 2, and 5, may be placed on both sides of the cylinders B, and these are strengthened to resist compression by bars of angle, T, or channel iron D riveted thereto.

When a floating foundation of the kind described is launched into the water, (it being launched sidewise and pushed by hydraulic jacks or their equivalents broadside into the water near to which it is built,) the foundation A, which is the only part of the entire structure necessarily subject to the operation of launching, will float with its top three or more feet above the surface of the water into which it has been launched. It is to be understood that the breakwater or superstructure carried upon my steady foundation A may be built upon the foundation A before or after launching the said foundation. If built after the launching of the foundation, then the upper part of the structure, consisting of the cylinders B and the rectangular portions C, together with the transverse bracing and internal staying of the cylinders B and rectangular portions C, is proceeded with until the structure carried upon my new or improved foundation is completed. When the breakwater, consisting of the cylinders B, rectangular parts C, and bracing I, has attained sufficient height above the foundation A, then water is admitted into the foundation by opening the water-admission valves, one of which (marked K) is indicated in Fig. 3, together with the screw-rod K' and hand-wheel K" for operating the same by turning the hand-wheel K" in either a right or left hand direction, and thereby opening or closing the valves K, as required. When it is desired to admit water into the cylinders B and rectangular portions D, another valve L and operative parts L' and L", like the parts K' and K", are operated to open and close the valve L' and admit water to any extent required into the lower part of the cylinders and rectangular portions B and C, respectively, until the foundation when completed 50 is in this manner sunk to its proper depth at the location where it is moored for carrying a floating breakwater.

At the top of each cylinder B a manhole M is provided for enabling access to be had to 55 the interior of the cylinders for examination, painting, and repairs.

As is shown by the transverse section, Fig. 3, the waves N of the water in which the foundation floats strike against the starboard 60 face of the steady floating superstructure, and there is smooth water O on the port side.

Instead of using cylinders B and rectangular intermediate portions C, as in Figs. 1 to 3, for being carried upon the steady floating foundations constituting my invention I

may use hollow conical frusta B' and triangular intermediate connecting-pieces C' between the conic frusta B', as shown at Figs. 4, 5, and 6. Conic frusta, such as those marked B', and triangular intermediate 70 pieces C', such as those shown at Figs. 4, 5, and 6, are indeed preferable to the cylinders B in Figs. 1, 2, and 3, for they constitute inclined as distinct from vertical surfaces for the waves to strike against and offer less resistance 75 to heavy wave-blows on the starboard side. Tubes, such as the tubes marked P, may be placed horizontally in the triangular partitions C', as shown in Figs. 3 and 6, also through the rectangular partitions C in Figs. 80 1 and 2.

Figs. 7, 8, 9, and 10 while showing the steady floating foundation illustrate it as carrying a breakwater or superstructure consisting of horizontal tubes Q, R, and S, 85 these tubes being attached to each other and to the flat bottom part A of the steady floating foundation by ties T T' T" T''' and by knees V, V', V'', and V''', as more clearly shown in the enlarged transverse sectional 90 view, Fig. 10.

While some forms of the foundation constituting my invention have hereinbefore been fully described and illustrated, it has not as yet been explained that irrespective 95 of the steady flotation obtained by immersion to a considerable depth of the foundation upon which the breakwater is carried the increased density of the water as the immersion of the foundation becomes deeper 100 conduces much additional steadiness to the structure apart from that due to the immersed weight alone. This fact of increasing density of water due to below-the-surface depth may be further advantageously 105 resorted to in connection with my invention when floating foundations corresponding therewith are to be placed in deep water. This is effected by applying long open-bottomed vertical tubes V to some or 110 all of the cylinders B shown at Figs. 1, 2, and 3 or to conic frusta B', Figs. 4 to 6. These tubes V are shown broken through in Fig. 11 in order to indicate that they may be of any desired depth and that they may 115 descend into depths of water of great density far below the depth of immersion of the foundation A in Figs. 1 to 11. In applying these tubes V the foundation, with its superstructure, is first towed and moored to its 120 locality, and the tubes V are then lowered through the conic frusta B' or cylinders B and are then bolted and stiffly secured to the parts B' or B by bolts V'' passed through the flanges V'. These steadyng-tubes do 125 not constitute any part of my present invention as hereinafter expressed in the claims.

In the circular foundation shown in elevation at Fig. 12 and in plan at Fig. 13 as carrying a steady floating circular fortress of 130

the kind described in my application for Letters Patent Serial No. 219,246, the general construction is the same as that already described, and in the construction of the bottom projecting member of the structure it is provided with receptacles Y, as in Figs. 1 to 10, for being loaded with gravel or other substance of greater density than the density of water, and for the purposes which have been hereinbefore described with reference to Figs. 1 to 10 it also depends for its steadiness and is maintained steadily floating by the weight carried in the receptacles of the structure and moored to anchors with slack cables, as hereinbefore described with reference to Figs. 1 to 15.

Having now described the nature of my said invention and the best system, mode, or manner in or under which the same is or may be used or carried into practical effect, I desire to observe in conclusion that what I consider to be novel and original, and therefore claim as the invention to be secured to me by Letters Patent, is as follows:

1. The steady floating foundation, consisting of a hollow braced and stiffened water-tight structure, upon which different kinds of superstructures are carried; the said foundation having a flange projecting be-

yond the width and length of the superstructure, carried thereon, said flange having receptacles for being loaded with water, and with another substance such as gravel, of greater density than water, in order to sink the foundation to the requisite depth for insuring steady flotation, substantially as hereinbefore described.

2. The steady floating foundation consisting of the combination of a hollow watertight structure or foundation a superstructure upon the same, a flange projecting outward from and constituting part of the said foundation, and surrounding the same, and projecting beyond said superstructure, said flange provided with receptacles or pockets adapted to be filled with water and with heavier substances in order to sink the foundation to the required depth, substantially as hereinbefore described.

In testimony whereof I, the said WILLIAM EDWARD MURRAY, have hereunto set my hand and seal this 28th day of February, 1905.

WILLIAM EDWARD MURRAY. [L. S.]

Witnesses:
